REFRIGERATING APPARATUS

Robert R. Candor, Dayton, Ohio, assignor to General Motors Corporation, Dayton, Ohio, a corporation of Delaware

Application April 30, 1934, Serial No. 723,173

17 Claims. (Cl. 62—115)

This invention relates to refrigeration and more particularly to the conditioning of air.

It is an object of this invention to provide a method and apparatus for conditioning air by which efficiency is increased, and power consumption decreased, with but slight and inexpensive changes in apparatus which has heretofore been used.

Further objects and advantages of the present invention will be apparent from the following description reference being had to the accompanying drawings, wherein a preferred form of the present invention is clearly shown.

In the drawings:

Fig. 1 is a diagrammatic representation of an apparatus embodying features of my invention;

Fig. 2 is a view somewhat similar to a portion of the apparatus shown in Fig. 1, showing a slightly modified form;

Fig. 3 is a view, partly in cross section, and partly diagrammatic of the application of my invention to a railway car or the like;

Fig. 4 is a diagrammatic plan view of a car to which my invention may be applied;

Fig. 5 is a plan view of the top of the air conditioner shown in Fig. 3; and

Fig. 6 is an enlarged vertical cross-sectional view of the top of the air conditioner shown in Fig. 3.

According to this invention, the efficiency of the usual multiple cylinder compressor used for air conditioning is greatly enhanced by a slight and inexpensive change in the valves, and without the necessity of changing the bore or volumetric capacity of the various cylinders. By this invention, air may be conditioned by evaporators which gradually decrease in temperature, and the various cylinders may be coordinated into the air conditioning scheme without the necessity of changing the main parts of the compressor. Usually a mere change in the valving structure of the compressor is sufficient to accomplish this end.

As shown in Fig. 1, air to be conditioned which may come from the outside atmosphere, or from an enclosure or both may be caused to flow in the form of a stream through a casing 10 by any suitable means as the motor driven fan 11 and the conditioned air is discharged into the enclosure. The stream of air first encounters the relatively warm evaporator 12 and then the relatively cold evaporator 13. Thus a certain portion of the heat from the air is removed therefrom at a relatively high refrigerant pressure or temperature in evaporator 12 and the last traces of heat are removed by a relatively low refrigerant pres-

sure or temperature in evaporator 13. The evaporated refrigerant from these evaporators is introduced into the compressing and condensing means at the proper stages of compression to obtain full advantage of my invention. Thus a compressor 14 is provided having a plurality of compressing chambers 15 and 16 which may be of substantially the same volumetric displacement. These chambers are provided with pistons 17 and 18 of substantially the same diameter and which are reciprocated by eccentrics on the shaft 19 having substantially the same throw. The check valves 20 and 21 are constructed to cause the flow of refrigerant vapor into the crankcase 22 and the valves 23 and 24 are constructed to cause a flow of refrigerant vapor from the crankcase 22. The suction outlet of the relatively cold evaporator 13 is connected by means of the line 25 with the intake 26 of the compressing chamber 16 from which the partially compressed refrigerant vapors are discharged into crankcase 22. The suction outlet of the evaporator 12 is connected by the line 27 with the crankcase 22. Here the vapors from evaporator 12 are commingled with the partially compressed vapors from evaporator 13 and enters the compression chamber 15. The discharge from the compressing chamber 15 is connected by the line 28 with the condenser 29 which is provided with the liquid receiver 30. From this receiver, liquefied refrigerant flows 30 through the line 31 through branches 32 and 33 to the evaporators 12 and 13 respectively for reevaporation.

The evaporator 12 is provided with an automatic expansion valve 34 which tends to feed liquid refrigerant into the evaporator when the pressure is reduced below a predetermined limit. However, this action is modified by a thermostatic bulb 35 placed near the refrigerant outlet of evaporator 12. This thermostatic bulb throttles the valve 34 when the liquid refrigerant tends to flow past the evaporator outlet into the line 27. A valve 36, similar to the valve 34, is placed at the inlet of the evaporator 13. A thermostatic bulb 37, similar to the bulb 35, is placed near the outlet of the evaporator 13 and throttles the valve 36 in the same manner.

As shown in Fig. 1, evaporated refrigerant from the evaporator 13 flows into the intake 26 of the compressing chamber 16. It then flows past the valve 20 and is forced on the upward stroke of the piston 18 into the crankcase 22. From thence it flows through the valved intake 23 of the compressing chamber 15 on the downward stroke of the piston 17, and is forced through the valve 24 55

into the outlet 38 on the up stroke of the piston 17. The refrigerant then flows to the condenser 29 where it is liquefied and is re-introduced into the evaporators through the expansion valves 34 and 36. Evaporated refrigerant from the warm evaporator 12 flows through the line 27 to the crankcase 22 where it is mingled with the partly compressed refrigerant from the evaporator 13 and enters therewith into the compression chamber 15, under the compressing action of the piston 17, and flows to the condenser 29 for reuse in the evaporator.

Automatic controls are provided. Thus a thermostat 39 may be placed in the enclosure which is supplied with air from the casing 10. This thermostat may operate a snap switch 40 which starts and stops the motor 41 which drives the compressor 14. The thermostat 39 may be calibrated to start the motor at a predetermined higher temperature limit and to stop the motor at a predetermined lower temperature limit. The flow of refrigerant through one of the evaporators may be controlled in accordance with slightly different air conditions. Thus the line 27 may be provided with throttling valve 42 which is actuated by a thermostat 43 also placed in the enclosure with the thermostat 39. The thermostat 43 may be calibrated at slightly higher temperature limits. Thus when the temperature in the enclosure drops to a predetermined higher limit, the valve 42 is throttled and thus a flow of refrigerant through the evaporator 12 is stopped. If the temperature in the enclosure drops to a still lower predetermined limit, the thermostat 39 stops the compressor 14. Thereafter, if the temperature rises to a predetermined limit, the thermostat 39 starts the compressor 14, and if the temperature rises to a still higher limit, the thermostat 43 opens the valve 42. The thermostats 39 and 43 may both be dry bulb thermostats or they may be both wet bulb thermostats or psychometers, or one may be a dry bulb and the other a wet bulb thermostat or a psychometer. At the present, it is preferable to have them both dry bulb thermostats.

In the modification shown in Fig. 2 the valve structure is slightly modified. Thus the relatively cold evaporator 13 may be connected by the line 50 with the compressing chamber 51. The refrigerant may enter past the check valve 52 on the down stroke of the piston 53. Refrigerant may be discharged past the check valve 54 on the up stroke of the piston 53 and may flow through the passage 55 into the crankcase 56 of the compressor. The relatively warm evaporator 12 may be connected by the line 57 with the crankcase 56. The commingled evaporated refrigerant from both evaporators may pass through the check valve 58 into the compression chamber 59 on the down stroke of the piston 60. These vapors may be discharged through the check valve 61 and the up stroke of the piston 60 and may flow through the line 62 of a condenser corresponding to the condenser 29. The volumetric displacement of the compressing chambers 51 and 59 may be substantially equal, and the remainder of the system may be as shown in Fig. 1.

In constructing compressors as shown in Figs. 1 and 2, the usual single stage multiple cylinder compressors may be used, which are generally provided with check valves in the pistons and at the cylinder heads in such a manner as to cause the flow of refrigerant in parallel relationship through the compression chambers. By changing the valve structures as shown in Figs.

1 and 2, stage compression may be obtained which may be coordinated with an air conditioning system to great advantage as described. While I have described certain features of my invention as particularly advantageous with compression chambers of substantially equal volumetric displacement these and other features may also be used where the compression chambers are not thus equal.

The air conditioning system shown in Figs. 1 and 2 may be of general application and may be used to condition air or similar gas wherever desired. One place where it is particularly advantageous and where electrical energy is at a premium is on railway cars, such as indicated in Figs. 3 to 6 inclusive. Thus the car may have a passenger enclosure 70. This enclosure may have one or more rows of seats 71 and 72, one on each side of the aisle 73. Between the seats on each row air conditioners 74 may be placed in parallel relationship with the long dimension of the seats. The air conditioners 74 may each take the form of a vertically disposed casing 75 which is relatively long in horizontal cross section and is adapted to fill the space between two seats, which may be placed back to back as shown in Fig. 3. A motor driven fan 76 may be placed in the casing together with a relatively warm evaporator 77 and a relatively cold evaporator 78. These members correspond to the fan 11 and evaporators 12 and 13 respectively in Fig. 1. Air from the enclosure 70 flows through inlet 79 past the relatively warm evaporator 77 under the impulse of fan 76 and then flows through a relatively cold evaporator 78 from which it is diffused into enclosure 70 in an upward direction through louvers 80 placed in the upper part of the casing 75. These louvers 80 may conveniently be made parallel with several of them slanting in one direction and several of them slanting in the other direction thus to spread the air upwardly and outwardly over the seats but above the head room of persons occupying the seats. A refrigerant compression system substantially as shown in Fig. 1 may be placed anywhere in the car. A thermostat 81 may control the suction line 82 of evaporator 77 in a manner similar to valve 42 and thermostat 43 in Fig. 1, while a thermostat 83 may control the starting and stopping of the motor, not shown, in a manner similar to the operation of thermostat 39 in Fig. 1. The motor may be driven from the usual electric storage battery system provided in railway cars or by any other electric system especially provided therefor, as desired.

While the form of embodiment of the invention as herein disclosed, constitutes a preferred form, it is to be understood that other forms might be adopted, all coming within the scope of the claims which follow.

What is claimed is as follows:

1. In combination a relatively warm evaporator, a relatively cold evaporator, compressing means and condensing means connected to withdraw evaporated refrigerant from said evaporators, compress and condense the same and return condensed refrigerant to said evaporators, said compressing means including compressing chambers of substantially the same volumetric displacement, the suction line from said cold evaporator being connected to the intake of one of said compressing chambers, the discharge from said last named compressing chamber and the suction line from said warm evaporator being connected to the intake of another of said compressing chambers.

2. In combination, a relatively warm evaporator, a relatively cold evaporator, compressing means and condensing means connected to withdraw evaporated refrigerant from said evaporators, compress and condense the same and return condensed refrigerant to said evaporators, said compressing means forming a plurality of compressing chambers and a crankcase, the suction line from said cold evaporator being connected to the intake of one of said compressing chambers, the discharge from said last named compressing chamber and the suction from said warm evaporator being connected to said crankcase, the intake of another of said compressing chambers being connected to said crankcase, and the discharge from said last named compressing chamber being connected to said condensing means.

3. An air conditioning apparatus comprising means creating a stream of air to be conditioned, a relatively warm evaporator and a relatively cold evaporator in thermal exchange relationship with said stream of air, compressing means and condensing means connected to withdraw evaporated refrigerant from said evaporators, compress and condense the same and return condensed refrigerant to said evaporators, said compressing means including a plurality of compressing chambers, the suction line from said cold evaporator being connected to the intake of one of said compressing chambers, the discharge from said last named compressing chamber and the suction line from said warm evaporator being connected to the intake of another of said compressing chambers.

35 4. An air conditioning apparatus comprising means creating a stream of air to be conditioned, a relatively warm evaporator and a relatively cold evaporator in thermal exchange relationship with said stream of air, compressing means and condensing means connected to withdraw evaporated refrigerant from said evaporators, compress and condense the same and return condensed refrigerant to said evaporators, said compressing means forming a plurality of compressing chambers and a crankcase, the suction line from said cold evaporator being connected to the intake of one of said compressing chambers, the discharge from said last named compressing chamber and the suction from said warm evaporator being connected to said crankcase, the intake of another of said compressing chambers being connected to said crankcase and the discharge from said last named compressing chamber being connected to said condensing means.

55 5. An air conditioning apparatus comprising means creating a stream of air to be conditioned, a relatively warm evaporator and a relatively cold evaporator in thermal exchange relationship with said stream of air, compressing means and condensing means connected to withdraw evaporated refrigerant from said evaporators, compress and condense the same and return condensed refrigerant to said evaporators, means controlling the operation of said compressing means in accordance with air conditions and means throttling the flow of refrigerant in one of said evaporators in accordance with other air conditions.

60 6. An air conditioning apparatus comprising means creating a stream of air to be conditioned, a relatively warm evaporator and a relatively cold evaporator in thermal exchange relationship with said stream of air, said evaporators being in series relationship in said stream of air, compressing means and condensing means connected to withdraw evaporated refrigerant from said

evaporators, compress and condense the same and return condensed refrigerant to said evaporators, said compressing means including a plurality of compressing chambers, the suction line from said cold evaporator being connected to the intake of one of said compressing chambers, the discharge from said last named compressing chambers and the suction line from said warm evaporator being connected to the intake of another of said compressing chambers.

65 7. An air conditioning apparatus comprising means creating a stream of air to be conditioned, a relatively warm evaporator and a relatively cold evaporator in thermal exchange relationship with said stream of air, said evaporators being in series relationship in said stream of air, compressing means and condensing means connected to withdraw evaporated refrigerant from said evaporators, compress and condense the same and return condensed refrigerant to said evaporators, said compressing means including a plurality of compressing chambers, the suction line from said cold evaporator being connected to the intake of one of said compressing chambers, the discharge from said last named compressing chamber and the suction line from said warm evaporator being connected to the intake of another of said compressing chambers means controlling the operation of said compressing means in accordance with air conditions, and means throttling the flow of refrigerant in one of said evaporators in accordance with air conditions.

8. An air conditioning apparatus comprising an enclosure, means creating a stream of air to be conditioned for said enclosure, a relatively warm evaporator and a relatively cold evaporator in thermal exchange relationship with said stream of air, compressing means and condensing means connected to withdraw evaporated refrigerant from said evaporators, compress and condense the same and return condensed refrigerant to said evaporators, means controlling the operation of said compressing means in accordance with air conditions in said enclosure and means throttling the flow of refrigerant in one of said evaporators in accordance with other air conditions in said enclosure.

9. A car having a passenger enclosure having a row of seats, an air conditioning apparatus for said enclosure comprising means creating a stream of air to be conditioned between two of said seats, a relatively warm evaporator and a relatively cold evaporator in thermal exchange relationship with said stream of air, compressing means and condensing means connected to withdraw evaporated refrigerant from said evaporators, compress and condense the same and return condensed refrigerant to said evaporators, means controlling the operation of said compressing means in accordance with air conditions in said enclosure.

10. A car having a passenger enclosure having a row of seats, an air conditioning apparatus for said enclosure comprising means creating a stream of air to be conditioned between two of said seats evaporating means in thermal exchange relationship with said stream of air, compressing and condensing means connected to withdraw evaporated refrigerant from said evaporating means, compress and condense the same and return condensed refrigerant to said evaporating means, and means controlling the operation of said compressing means in accordance with conditions in said car.

11. A car having a passenger enclosure having

a row of seats, an air conditioning apparatus for said enclosure disposed between two seats comprising means creating a stream of air and cooling means in thermal exchange relationship with said stream of air.

5. 12. A car having two rows of seats, one on each side of an aisle, an air cooler on one side of said aisle between two seats and an air cooler on the other side of said aisle arranged to cooperate with 10 the first named cooler to create a circulation of conditioned air within the car.

13. A car having two rows of seats, one on each side of an aisle, an air cooler on one side of said aisle between two seats and an air cooler on the other side of said aisle said coolers discharging 15 cooled air upwardly and cooperating to create a current of conditioned air within the car.

14. The method of conditioning air which comprises flowing air in a stream, thermally contacting 20 said stream with a volatile refrigerant in a first zone maintained at a relatively warm evaporating temperature, thermally contacting said stream with a volatile refrigerant in a second zone maintained at a relatively cold evaporating temperature, compressing refrigerant vapors from 25 said second zone in a first compressing stage, mixing the vapors thus compressed with refrigerant vapor from said first zone and compressing the commingled vapors, condensing the vapors thus 30 compressed and re-evaporating them in said zones.

15. The method of conditioning air which comprises flowing air in a stream, thermally contacting 35 said stream with a volatile refrigerant in a first zone maintained at a relatively warm evaporating temperature, thermally contacting said stream with a volatile refrigerant in a second zone maintained at a relatively cold evaporating temperature, compressing refrigerant vapors from 40 said second zone in a first compressing stage, mixing the vapors thus compressed with refrigerant vapor from said first zone and compressing the

commingled vapors, condensing the vapors thus compressed, reevaporating them in said zones, controlling the evaporation in one of said zones independently of the other zone in accordance with air conditions and starting and stopping the 5 compression of refrigerant vapors in accordance with air conditions.

16. In combination, a relatively warm evaporator, a relatively cold evaporator, compressing means and condensing means connected to withdraw evaporated refrigerant from said evaporators, compress and condense the same and return 10 condensed refrigerant to said evaporators, said compressing means having substantially the same volumetric displacement for each evaporator, the 15 suction line from said cold evaporator being connected to the intake of one of said compressing means, the discharge from said last named compressing means and the suction line from said warm evaporator being connected to the intake 20 of another of said compressing means.

17. In a combination, a relatively warm evaporator, a relatively cold evaporator, compressing means and condensing means connected to withdraw evaporated refrigerant from said evaporators, compress and condense the same and return 25 condensed refrigerant to said evaporators, said compressing means having only two compressing chambers both of which have substantially the same volumetric displacement, and a 30 crankcase, the suction line from said cold evaporator being connected to the intake of one of said compressing chambers, the discharge from said last named compressing chamber and the suction 35 from said warm evaporator being connected to said crankcase, the intake of another of said compressing chambers being connected to said crankcase, and the discharge from said last named compressing chamber being connected to said condensing means.

ROBERT R. CANDOR.
